United States Patent

Des. 242,273
Patented Nov. 9, 1976

242,273

TOY TRUCK

Robert Brass, 4 Norwood Lane,
Westport, Conn. 06880

Filed Jan. 29, 1975, Ser. No. 544,873

Term of patent 14 years

Int. Cl. D21—01
U.S. Cl. D34—15 AJ

Fig. 1.

Fig. 2.

Fig. 4.

Fig. 3.

FIG. 1 is a top plan view of a toy truck showing my new design;

FIG. 2 is a side elevational view thereof, the side opposite being substantially a mirror image;

FIG. 3 is a front elevational view thereof; and

FIG. 4 is a rear elevational view thereof.

I claim:

The ornamental design for a toy truck, as shown and described.
